[57] CLAIM

The ornamental design for animal feeding bowl, as shown and described.

DESCRIPTION

FIG. 1 is an exploded perspective view of an animal feeding bowl showing my new design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is another perspective view thereof.

The broken lines in FIGS. 1 and 7 are for purposes of illustration only and form no part of the claimed design.
